UNITED STATES PATENT OFFICE.

EDWARD R. CONNELLY, OF BOSTON, MASSACHUSETTS.

OUTSOLE FOR SHOES.

Continuation of application filed November 4, 1921, Serial No. 512,711. This application filed October 2, 1925. Serial No. 60,100.

The invention to be hereinafter described relates to shoes, and more particularly to soles of shoes.

When ordinary shoes are worn, the outer edges of the widest part of the sole and the toe thereof turn up, thereby producing a depression in the sole beneath the anterior or transverse arch of the foot.

As a consequence, the anterior arch may drop into this depression, take the support from the proper bearing points, which are the joints of the great and little toes, and thereby cause pain and callouses.

Localization of the pressure on the center of the sole causes the wear to be concentrated at one spot; causes the ball of the foot, which is its most sensitive part, to receive painful pressure from pebbles and stones; and brings the ball of the foot close to damp, cold ground, with consequent liability of causing colds.

When the anterior arch of the foot drops into the depression, the top part of the foot drops from the upper, and its snug fit is lost, so that proper support for the ankle and longitudinal arch is no longer had, and friction occurs between the upper and the toes of the foot, frequently causing corns.

This depression and falling of the anterior arch also cause spreading of the foot, longitudinal curving of the sole, wrinkling of the upper, and improper distribution of wear on the heels, so that the desirable appearance of new shoes is soon lost.

I am aware that heretofore appliances have been devised which are intended for insertion in shoes to correct deformation of the anterior arch, but these devices are not inherent to the shoe as originally constructed, and therefore they do not operate to prevent distortion of the anterior arch, but rather as means to correct trouble already caused. Also these appliances are difficult to apply properly; they are liable to become displaced; they are expensive, and do not prevent the distortion of the shoe.

An aim and purpose of the present invention, therefore, is to so construct shoes and particularly new shoes that the anterior arch of the normal foot will be properly supported and dropping of the arch will be prevented, and so that new and repaired shoes may be worn with comfort by persons whose anterior arches have fallen.

To accomplish this, I have provided an outer sole having a member extended upwardly from its upper surface at or nearest its widest part and firmly attached thereto intermediate its side edges to leave substantially flat side bearing surfaces for the joints of the big and little toes and to form a reinforcement for the outsole between said side bearing surfaces, and said reinforcing member is suitably shaped and located so as to form a support for the bones of the three toes intermediate the big and little toes under the metatarsal arch without disturbing the bearings of the joints of the big and little toes and of the heel of the foot and yet not afford any material support for the longitudinal arch of the foot.

The reinforcing member may and preferably will be substantially dome-shaped of gradual inclination or curvature and is preferably located with its highest point between a vertical plane extended transversely of the outsole at its widest part and substantially at right angles to the longitudinal axis of the outsole, and a vertical plane extended at an acute angle to the said longitudinal axis and passing through the joint of the big toe and the front joint of the little toe.

The sole-reinforcing and arch-supporting member forms a permanent part of the outsole and is firmly attached or secured thereto. When the outer sole is made of materials capable of being molded, as, for instance, rubber compositions, the sole-reinforcing and arch-supporting member may be made as an integral part of the outsole, and when the outsole is made of leather or like non-moldable material, the said member may be cemented, sewed or otherwise secured in fixed relation to the outsole.

The particular features of the invention will be pointed out in the claims at the end of this specification.

Fig. 1 is a plan view on an enlarged scale of an outsole embodying this invention, and showing also in dotted lines the bones of the foot.

Fig. 2 is a view partly in elevation and partly in vertical section of a shoe provided with the outsole shown in Fig. 1.

Fig. 3, a vertical transverse section taken on the line 3—3, Fig. 2.

Fig. 4, a transverse section of a modified form of outsole showing the reinforcing and

supporting member cemented thereto, and

Fig. 5, a transverse section of another modified form of outsole showing the reinforcing and supporting member stitched thereto.

The invention may be embodied in welt, McKay, turned or stitched-down shoes, but for purposes of illustration, it is shown herein as embodied in a welt shoe.

Referring to the drawing, the welt shoe shown therein comprises an upper 1, insole 3 and welt 5 secured together by stitching 7 in the usual manner.

The outsole 9 may be leather, rubber or composition, and is secured to the welt by stitching 11 in the usual manner.

In the present instance of the invention, the outsole is provided with a dome-like protuberance 13 of gradual inclination projecting upward from the outsole intermediate the edges of the sole which are widest apart, and spaced somewhat from said edges to leave substantially flat bearing surfaces 14, 15 for the joint 16 of the big toe and the front joint 17 of the little toe of the foot.

The construction is such that the protuberance is positioned to furnish support to the anterior or transverse arch of the foot formed by the second, third and fourth metatarsal bones of the foot. As a consequence, the natural form of the arch is maintained, and the weight of the fore portion of the foot is thrown on the proper bearing points, which are the joints of the great and little toes.

The dome-like protuberance may be formed of the same material as the outsole, either integrally therewith as represented in Fig. 3, or of a properly formed segment 40 which may be cemented thereto as represented in Fig. 4, or otherwise permanently secured to the outsole as by stitches 20 as represented in Fig. 5. Therefore, this protuberance constitutes a part of the outsole 45 and of the shoe as originally made, contradistinguished from appliances which are inserted in shoes already constructed. These appliances are removable, whereas, the protuberance of a shoe embodying this invention is a permanent characteristic of the original shoe, or of a shoe which has been resoled with the outsole and cannot be removed without taking off the outsole.

The dome-like protuberance forming a permanent part of the outsole and being firmly attached thereto adds desirably to the thickness of the outsole beneath the ball of the foot, and constitutes a reinforcing member for said outsole, and therefore tends to prevent curling up of the outsole transversely and longitudinally and maintains the bearing surfaces 14, 15 for the big and little toes in a substantially flat condition.

The reinforcing member 13 for the outsole is located with the highest point at the

rear of a vertical transverse plane passing through the joint 16 of the big toe and the front joint 17 of the little toe and represented in Fig. 1 by the line 25, and for the best results said highest point is located substantially in a vertical transverse plane passing through the outsole at its widest part and represented by the line 26.

By reference to Fig. 1, it will be observed that the transverse plane 25 is inclined with relation to the longitudinal axis 27 of the outsole, and the transverse plane 26 is substantially at right angles to said axis.

Furthermore the projecting member 13 is for the best results made of such size and shape as to have its front portion extend forward beyond the inclined vertical plane 25 and under the joints 30, 31, 32 of the three intermediate toes, which joints form the intermediate members of the metatarsal arch.

Also for the best results, the projecting member 13 is made of a width which is less than the distance between the bones of the big and little toes, so that the bearing of the joints 16, 17 of the latter upon the flat bearing surfaces is not lessened.

While it is preferred not to extend the projecting member under the bones of the big and little toes it is not desired to limit the invention in this respect, as the projecting member 13 may be extended partially under the big and little toes with diminishing efficiency so long as the joints 16, 17 of said toes bear upon the substantially flat bearing surfaces.

It will thus be observed that the outsole is provided with a member projecting from its upper surface which forms a permanent part of the outsole, and reinforces the same so as to resist curling of the outsole and the consequent formation of a concavity in the outsole.

It is also located with respect to the side edges of the outsole so as to leave substantially flat surfaces at the sides of the outsole for the joints of the big and little toes to bear upon.

It is further located with its highest point at the rear of a transverse plane passing through the joints of the big and little toes and inclined with relation to the longitudinal axis of the outsole and preferably substantially in a transverse plane passing through the outsole substantially at its widest part and substantially at right angles to the longitudinal axis so as to co-operate with the metatarsal arch to form a support for the joints of the three intermediate bones of said arch while permitting the joints of the outside or end bones of said arch to bear upon the substantially flat side bearing surfaces and be supported thereby.

As a result, the outsole when incorporated in a new shoe or in a resoled shoe, prevents falling of the metatarsal arch of a normal

foot and raises and maintains raised the metatarsal arch which has fallen and restores a foot having a fallen arch to its normal condition.

5 In practice the relation of the sole reinforcing and arch-supporting member to the outsole will be maintained in outsoles of different sizes and the size of the said member will vary in accordance with the variation in 10 the sizes of the outsoles.

Since the sole-reinforcing and arch-supporting member prevents the formation of the depression or concavity in the sole, it does not allow the foot to drop down from 15 the upper, and as a result, the latter will always fit snugly to the foot, preventing wrinkling and other distortion of the upper, and tends to maintain the original desirable appearance of the shoe as a whole.

20 Since the anterior or transverse arch is not allowed to drop, the foot is narrower and shorter than it would be if the arch were deformed and consequently, a shoe of smaller size is required.

25 The added thickness to the outsole increases the life thereof and protects the sole of the foot from cold and dampness, and from being sensitive to pebbles and stones.

The protuberance on the outsole in holding 30 the foot up in snug fitting relation with the upper, causes the latter to give added support to the foot as a whole, and properly sustains the longitudinal arch and ankle. The snug fit thus obtained also prevents rubbing and friction between the foot and the 35 upper, and prevents formation of corns and callouses.

Since the fore part of the foot is thrown 40 on its proper bearing points which, as stated, are the great and little toe joints, the weight is desirably distributed transversely on the sole, and as a consequence, the weight will not be thrown to one side and cause the heel of the shoe to wear unevenly.

45 When the sole becomes worn and it is desirable to have the same resoled, a new sole provided with the anterior arch-supporting protuberance can be supplied and attached to the welt in the usual manner.

50 From the above description and by reference to Fig. 1, it will be seen that the diameter of the dome-shaped member is materially less than the outsole at its widest part so as to leave substantially flat bearing 55 surfaces for the joints of the big and little toes at the opposite sides of the sole, and that the distance the arch-supporting member is extended longitudinally of the sole, is limited, and is localized, so that it extends 60 for relatively short distances toward the shank and forepart of the outsole.

The arch-supporting and reinforcing member diminishes in thickness forwardly and rearwardly of the widest part of the outsole and gradually merges with the outsole

and the rear portion of said member merges with the shank portion of the outsole in close proximity to the center of the arch-supporting member, thereby leaving the shank portion of the outsole for the greater portion 70 of its length of normal thickness and flexibility, and leaving the longitudinal arch of the foot unsupported for the greater portion of its length, which is highly desirable, as it avoids distortion and strain upon the 75 foot, while providing the desirable three-point bearing for the foot, to wit: at the heel, and the joints of the big and little toes.

The arch-supporting member diminishes in thickness forwardly and gradually merges 80 with the outsole in close proximity to the center of the said member so as to support the metatarsal arch without disturbing the bearings of the big and little toe joints upon the substantially wide, flat surfaces at the 85 sides of the outsole.

It will thus be understood that the invention is not limited to the specific embodiment shown, and that various deviations may be made therefrom without departing from the 90 spirit and scope of the appended claims. In Fig. 4, the cement is represented by the heavy line 30:

This application is a continuation of my application Serial Number 512,711 filed November 4, 1921 for improvement in shoes.

What is claimed is:

1. As an article of manufacture, an outsole for a shoe provided with a dome-like integral protuberance projecting upwardly 100 from and above the upper surface thereof at the widest portion of the sole to furnish support for the anterior arch of the foot of the wearer and extending lengthwise of said outsole for a relatively short distance with 105 its front and rear extremities in substantially close proximity to the center of said dome-like protuberance.

2. As an article of manufacture, an outsole for a shoe provided with a substantially flat 110 upper surface and having a substantially dome-like protuberance attached to said outsole to form a permanent part thereof and projecting upwardly from and above said upper surface at the widest portion of the 115 outsole to furnish support for the anterior arch of the foot of the wearer and to leave bearing surfaces in substantially the same horizontal plane for the big and little toes of said wearer, and extending lengthwise of 120 said outsole for a relatively short distance with its front and rear extremities in substantially close proximity to the center of said dome-like protuberance.

3. As an article of manufacture, an outsole provided with a substantially flat upper surface and having a member projecting upwardly above its upper surface and attached in fixed relation to said upper surface substantially at its widest portion to reinforce 125

the outer sole in thickness between its side edges and leave substantially flat bearing surfaces in substantially the same horizontal plane at opposite sides of the outsole, and having its highest point located at the rear of a transverse plane passing through the bearing surfaces for the joints of the big and little toes of the foot supported by said outsole and having its front and rear extremities in substantially close proximity to ¹⁰ said highest point.

In testimony whereof, I have signed my name to this specification.

EDWARD R. CONNELLY.
